UNITED STATES PATENT OFFICE.

HERBERT L. JOHNSTON AND MILTON K. AKERS, OF TROY, OHIO, ASSIGNORS TO THE HOBART MANUFACTURING COMPANY, OF TROY, OHIO, A CORPORATION OF OHIO.

SHORT-CIRCUITING DEVICE FOR ELECTRIC MOTORS.

Application filed March 23, 1925. Serial No. 17,522.

Our invention relates to devices for use in connection with alternating current motors when it is desired to change the operation of such motors from repulsion to induction when a predetermined speed has been reached.

This change is accomplished by short circuiting the commutator of a wound rotor.

Among the objects of our invention is the provision of simple means for accomplishing such a short circuiting, whereby a single spring, whose action is readily adjustable and which acts as a compression spring, opposes the action of the short circuiting disk. 15 The parts are held together without screws and can be quickly assembled and installed. The short circuiting element is in the form of disk having a resilient edge, which will contact evenly and the take-up for the action of the spring and the disk is accomplished by pressing in on certain parts against the spring and turning them through part of a revolution.

These objects and other advantages to be noted, we accomplish by that certain construction and arrangement of parts to be hereinafter more specifically pointed out and claimed.

In the drawings:

30 Figure 1 is a central vertical elevation, partly broken away, taken through the device, showing relative position of parts when the motor is stopped or operating as a repulsion motor.

35 Figure 2 is a central vertical section taken through the device, showing the parts in the positions they take when the motor is up to speed and operating as an induction motor.

40 Figure 3 is a perspective view of one of the weight bars.

Figure 4 is a perspective view of the short circuiting disk.

45 Figure 5 is a perspective view of the adjustable hub.

We have not shown the parts of a motor aside from the armature shaft and the commutator bar holder casting thereon. It will be understood that any usual form of alternating current motor and brush device may be employed.

On the shaft 1 of the armature is mount-

ed the commutator casting 2, in which are the commutator bars 3 insulated from the casting at 4.

55 A plate 5 is provided having a hub 6, which fits slidably over the armature shaft and is held inwardly toward the commutator by means of a pin 7 set into the shaft at a proper point. The commutator casting is shown as formed with a depression 2^a, which acts as a housing for parts of the device. It will be understood that this exact method of housing the parts need not be followed except for the saving of space 60 and saving of size in the short circuiting disk.

65 The hub 6 has a series of notches 8 cut therein, the notches opposite each other having the same depth, but each opposed pair 70 varying in depth. This permits of adjusting the position of the hub along the shaft.

Over the armature shaft, inside of the hub 6, is set a sleeve 9, which carries in a groove therein, the short circuiting disk 10. 75 This disk is cup-shaped so as to bring its edges into proper position with relation to the ends of the commutator bars, which are exposed at the outer face of the commutator casting.

80 The disk is formed at its edges with a series of slots 11, which separate the edges into a series of interspaced tongues which have considerable resiliency. The body of the disk has a series of rectangular slots cut 85 therein, as at 12, in which are to be set the centrifugally controlled elements.

85 These centrifugally controlled elements are formed as heavy pieces having bars 13, which lie normally in line with the armature shaft. 90 They have necks 12^a which lie in the slots in the disk 10. We have also shown an additional disk or washer 15, which is mounted with the disk 10, and is used for purposes of stiffness.

95 The weights have also angle ends 14, which lie normally flat against the plate 5, same being part of the hub 6.

A spring 16, of carefully arranged strength, is inserted over the armature shaft and the remaining parts are assembled and thrust over the shaft. The pin 7 is then set in place and the selected notches of the hub 6 set over the pin. This will place the

spring 16 under tension, which can be varied by changing the notches of the hub which engage the pin.

In operation the motor will start as a repulsion motor and as it gains speed the weights or centrifugal members will tend to fly out centrifugally, so as to tip on the plate 5, the outer corners of the portion 14 acting as the fulcrum. The weights will also tend to rock within the slots of the short circuiting disk and washer.

This action will force the short circuiting disk away from the plate 5 toward the commutator bar ends until the resilient edge of the disk contacts with the bars and short circuits the armature coils.

The spring 16 opposes this action, since it presses on the sleeve 9 that carries the short circuiting disk, and the washer when it is used also.

The fact that the spring acts as a compression spring gives more lift and uniform action thereto, and the tension of the spring is readily adjusted as noted. The resilient tongued edge of the disk acts effectively to short circuit all bars and the disk is so mounted on the sleeve 9 that it must move axially to the armature shaft so as to make a uniform contact.

The weights will return to normal position as soon as the motor slows down to a stop, ready to begin the cycle over again when it is started up.

As stated above, we do not wish to be construed as limiting our invention to one set of mechanism, because of our failure to describe such alternative structures as appear to us readily usable instead of those described.

Having thus described our invention, what we claim as new and desire to secure by Letters Patent, is:—

1. In combination with an armature shaft,

a commutator having bars, a sleeve on the shaft, a short circuiting disk on the sleeve, spring means to hold the disk away from short circuiting position, centrifugal means and a relatively fixed member on the shaft, between which and the short circuiting device the centrifugal means acts, said member being adjustable along the shaft, said adjustment comprising a pin in the shaft and a hub having a series of opposed notches to engage the pin, said notches having varying depth.

2. In combination with an armature shaft, a commutator having bars, a sleeve on the shaft, a short circuiting disk on the sleeve, spring means to hold the disk away from short circuiting position, centrifugal means and a relatively fixed member on the shaft, between which and the short circuiting device the centrifugal means acts, said member being adjustable along the shaft, said adjustment comprising a pin in the shaft and a hub having a series of opposed notches to engage the pin, said notches having varying depth, and said disk having a resilient edge for contact with the ends of the commutator bars.

3. In combination with an armature shaft, a commutator having bars, a sleeve on the shaft, a short circuiting disk on the sleeve, a coil spring concentrically mounted on said shaft for holding said disc away from short circuiting position, centrifugal means for moving said disc to short circuiting position, an adjustably mounted member on said shaft between which and the short circuiting device said centrifugal means acts, and the adjustability of said member for varying the tension of said spring being provided by pin and slot connections.

HERBERT L. JOHNSTON.
